UNITED STATES PATENT OFFICE

LEO EDELMANN, OF CHICAGO, ILLINOIS, ASSIGNOR TO E. EDELMANN & CO., OF CHICAGO, ILLINOIS, A CORPORATION OF ILLINOIS

PROTECTIVE DEVICE FOR HYDROMETERS

Application filed February 16, 1929. Serial No. 340,371.

My invention relates to protective devices for hydrometers and particularly to a structure intended and adapted for use in protecting the glass barrel of syringe hydrometers such as are used in testing battery solutions and the like.

An object of this invention is to provide a protective device which can be applied upon various types of hydrometers and which will 10 protect the glass hydrometer barrel adjacent the nozzle.

Another object is to so form and construct the parts that a better connection will be provided at the point of attachment between the barrel and nozzle.

With the above and other objects in view which will be apparent to those skilled in the art, my invention includes certain novel features of construction and combinations of 20 parts which will be hereinafter set forth in connection with the drawing.

In the drawing:

Figure 1 is a view in perspective showing a hydrometer constructed in accordance with 25 my invention.

Fig. 2 is a fragmentary view of the nozzle end of the hydrometer structure with parts broken away to better show the construction and mounting of the elements.

30 Figs. 3 and 4 are views similar to Fig. 2 showing modifications.

Fig. 5 shows another modification.

Where hydrometers, of the battery testing type, are made up with a glass barrel having a rubber nozzle tip provided with a 35 plug portion to be inserted in one end of the barrel for attachment and assembly of the two parts, it has been found that the rubber of the plug portion will shrink permitting leakage of battery acid or other liquids being tested. Also, with this construction the end of the glass barrel is exposed in such a manner that it is likely to become broken during 40 the assembly of the parts and when the instrument is in use.

With the above in mind I propose to provide a protective device which will give protection against breakage of the glass barrel 50 and will also protect against leakage of the

liquid from the barrel by forming a better connection between the parts.

In the present instance I have shown my invention applied in conjunction with a hydrometer of the ordinary glass barrel syringe type, in which the glass barrel 1 adapted to contain the float element 2 has a bulb 3 mounted at one end and a nozzle 4 fitted at the remaining end. This nozzle 4, referring to the disclosure in Figs. 1 and 2 has a plug 55 portion 5 adapted to be pushed into the open end of the barrel 1 to mount the nozzle 4 in place and close the end of the barrel; however, as pointed out above the stopper portion 5 offers no protection for the end of the barrel 1 and this portion will shrink in use 60 sufficiently to permit leakage of liquid from the barrel while tests are being made.

A flange portion 6 is provided around the nozzle 4 adjacent the plug portion and a protective sleeve 7 is fitted upon the end of barrel 1 to embrace and contact with the flange 6. With the protective sleeve mounted in this manner the end of the barrel 1 is protected 65 against contact and shocks which would cause 70 breakage, and the portion of the sleeve 7 fitting tightly in contact with flange 6 will provide a double seal against the leakage of liquid from the nozzle end of the barrel. Any shrinkage in the material of the flange 6 will 75 not cause leakage as the protective sleeve 7 will shrink correspondingly and a tight connection and contact is thus maintained at all times. This protective ring 7 can be formed with a bead 8 or other extending portion to 80 cooperate with the bulb 3 in raising the unprotected middle portion of the barrel 1 from contact with a flat or somewhat rounded surface.

With the modified construction illustrated 90 in Fig. 3 the flange 6^a on the nozzle portion 4^a adjacent the plug portion 5^a is made of a diameter slightly larger than the outside diameter of the glass barrel 1^a and when the protective sleeve 7^a is fitted in place over this flange it will be slightly stretched and placed 95 under tension so that a liquid-tight contact and connection will be maintained at all times. In this adaptation the protective bead or flange 8^a is formed as a part of the nozzle por- 100

tion and is made polygonal to present flat sides which will prevent rolling.

With the parts as illustrated in Fig. 4 the head flange 8^b is provided around the nozzle portion 4^b adjacent the plug portion 5^b and the protective ring 7^b fitted on the end of the glass barrel 1^b is brought into contact with the bead portion of the nozzle to entirely cover the end of the glass barrel.

10 As the parts are illustrated in Fig. 5, the flange 6^c on the nozzle portion 4^c adjacent the plug portion 5^c is of a diameter corresponding substantially to the end of the barrel 1^c. The protective sleeve 7^c is adapted to 15 be fitted in place to be threaded or slipped over the nozzle end and the flange 8^c holds the parts assembled.

In assembling the parts of my invention the protective ring 7, 7^a or 7^b can be fitted 20 upon the end of the glass barrel and the plug portion 5, 5^a or 5^b of the nozzle member is then fitted in place within the end of the glass barrel following which the protective sleeve or ring 7, 7^a or 7^b is slid downwardly 25 along the glass barrel to the proper contact with the nozzle member.

While I have herein shown and described only certain specific embodiments of my invention and have suggested only certain possible modifications, it will be appreciated that many changes and variations can be made in the form, construction, arrangement and assembly of the parts without departing from the spirit and scope of my invention.

35 I claim:

1. In combination with a hydrometer having a frangible barrel, a nozzle provided with a plug portion to be fitted into one end of the barrel, and a protective sleeve fitted on 40 said end of the barrel in contact with the nozzle portion adjacent the plug thereof.

2. In combination with a hydrometer having a frangible barrel, a nozzle provided with a plug portion to be fitted into one end of the barrel, and a protective sleeve fitted on 45 said end of the barrel in contact with the nozzle portion adjacent the plug thereof, said nozzle portion having a flange with which said protective sleeve engages.

50 3. With a frangible hydrometer barrel, a nozzle provided with a plug portion to fit within one end of the barrel, said nozzle having a flange portion extending adjacent the end of the barrel when the plug portion is in 55 place, and a protective sleeve fitted upon the end of said barrel and in contact with the flange portion of the nozzle.

4. With a frangible hydrometer barrel, a nozzle provided with a plug portion to fit 60 within one end of the barrel, said nozzle having a flange portion extending adjacent the end of the barrel when the plug portion is in place, and a protective sleeve fitted upon the end of said barrel and in contact with the 65 flange portion of the nozzle, said protective

sleeve being extended longitudinally beyond the end of the barrel to receive and close around said flange portion of the nozzle.

In testimony whereof I hereunto affix my signature.

LEO EDELMANN.
